John McKillop

United States Patent Office.

JOHN MCKILLOP, OF BROOKLYN, NEW YORK, ASSIGNOR TO ANDREW MACKEY AND JOHN WARD, JR., OF SAME PLACE.

Letters Patent No. 78,583, dated June 2, 1868.

IMPROVEMENT IN SAFETY-BRIDLES.

The Schedule referred to in these Letters Patent and making part of the same.

TO ALL WHOM IT MAY CONCERN:

Be it known that I, JOHN MCKILLOP, of Brooklyn, in the county of Kings, and State of New York, have invented certain new and useful Improvements in Safety-Bridles; and I do hereby declare that the following is a full, clear, and exact description of the same, reference being had to the accompanying drawings, making a portion of this specification, in which—

Figure 1 is a side view, showing the manner of applying my invention to a bridle.

Figure 2 is a plan view, on an enlarged scale, of an apparatus made according to my invention.

Similar letters of reference indicate corresponding parts in both figures.

The object of this invention is to provide a means whereby a refractory horse may be readily and effectually choked into submission.

The invention consists in an apparatus composed of two lever-jaws, so combined that when applied to the "throat-latch" of the bridle, and furnished with a suitable rein, they may be conveniently and forcibly compressed upon the throat or windpipe of the horse, thereby securing the end above named.

The invention further consists in the combination of a spring with the lever-jaws in such manner as to retain the same away from the throat of the animal when it is not desired to operate the device.

To enable others to understand the construction and operation of my invention, I will proceed to describe it with reference to the drawings.

Represented at A are two lever-jaws, pivoted together at their inner ends by a pin or pivot, the head, a', of which is made ring-shaped, to receive a ring or link, a, passing loosely through the same. The innermost portion, b c, of these jaws is made of curved form, as represented more fully in fig. 2, and the outer portions are turned outward at an angle thereto, as shown at b d, in the same figure, and have provided therein loose rings, e.

Provided at the outer side of each of the jaws, at or near the middle of the curved portions, b c, thereof, are broad-headed screws or pins, b', which pass through oblong slots provided in the end-portions of a curved spring, f, applied outside of and around the inner ends of the curved portions, b c, of the two jaws, as represented more plainly in the fig. 2, just mentioned, in such manner as to tend to draw the jaws outward, away from each other, such outward movement of the jaws being limited by the striking together of shoulders provided thereon, at the outer side of the pivot, by which they are connected, as hereinbefore set forth.

The bridle itself may be of any suitable kind, and, in using the apparatus, the throat-latch, indicated at g in fig. 1, of the bridle is passed through the ring or link a, the apparatus being thus suspended therefrom, and a rein, shown at m, having its two ends attached, one to each of the rings e, is carried over the horse's neck, in such a manner that by drawing thereon, the two jaws will be brought astride of the throat or windpipe of the animal, with the outwardly-bent portions, b d, extending laterally therefrom, whereupon, the force exerted upon the rein being continued, the jaws are brought inward toward each other, compressing the windpipe between them, thus choking and consequently subduing the animal to obedience and submission. When the rein is relaxed, the spring f serves to bring the jaws away from the throat or windpipe of the horse, thus releasing the latter.

What I claim as my invention, and desire to secure by Letters Patent, is—

1. The choking-apparatus, composed of the two lever-jaws, constructed and combined for operation, substantially as and for the purpose specified.
2. The combination of the spring f with the two lever-jaws, A, of the choking-apparatus, substantially as and for the purpose specified.
